UNITED STATES PATENT OFFICE.

EUGÈNE EXCOFFIER, OF CHÂTELAINNE, NEAR GENEVA, SWITZERLAND.

CARBURETER.

1,280,004.

Specification of Letters Patent. Patented Sept. 24, 1918.

Application filed November 11, 1915. Serial No. 60,832.

To all whom it may concern:

Be it known that I, EUGÈNE EXCOFFIER, a citizen of Switzerland, residing at Châtelaine, near Geneva, in the Confederation of Switzerland, have invented certain new and useful Improvements in Carbureters for Explosion-Motors, of which the following is a specification.

This invention relates to carbureters particularly adapted for use in explosive engines and more especially to that class of carbureters in which there is maintained a definite relationship between the area of the discharge port for the liquid fuel and the passage through which the explosive mixture is admitted to the engine.

In carrying out my invention I preferably employ but one spraying nozzle fitted with a device for controlling the discharge port for the liquid fuel in such a manner that this discharge port is open to a predetermined extent or closed. I also employ a diaphragm, preferably an iris diaphragm situated in the passage through which the combustible mixture passes to the engine, and means for controlling the opening in the diaphragm and also the devices for opening and closing the discharge port in the spraying nozzle for the liquid fuel so that as hereinbefore stated there is always a predetermined relationship between the opening in the diaphragm and the extent to which the discharge port is open. Moreover the discharge port in the spraying nozzle is so placed as to be centrally disposed to the opening in the iris diaphragm at all times. I also employ a supply tank together with means for maintaining the level of the liquid fuel at a predetermined height as well as means associated with the spraying nozzle and open to communication with the supply tank when the discharge port is closed for receiving a charge of liquid fuel which materially assists in the subsequent starting of the engine. The particular construction of these improvements will be hereinafter more particularly described.

In the drawing:-

Figure 1, is a central vertical cross section of a carbureter illustrating my present invention.

Fig. 2, is a divided view showing in cross section the parts which when assembled comprise the neck member in which the iris diaphragm is mounted.

Fig. 3, is an elevation of the base of the carbureter body.

Fig. 4, is a plan of the parts comprising the diaphragm.

Fig. 5, is a similar view showing the body 60 of the carbureter in cross section and the plates of the diaphragm in a different position.

Fig. 6, is an inverted plan of the dia- 65 phragm members.

Fig. 7, is a divided view showing in plan and central cross section the ring employed to maintain the diaphragm plates in position and take up the wear of the same.

Fig. 8, is a plan of the spring member 70 employed in conjunction with the ring shown in Fig. 7 to assist in maintaining the diaphragm plates in position.

Fig. 9, is a plan of the movable ring for actuating the diaphragm plates. 75

Figs. 10, 11 and 12, are enlarged plans showing the end of the spraying nozzle and the controller sleeve for determining the extent to which the discharge port is open.

Fig. 13, is a divided view showing in plan 80 and central cross section the plate employed in the lower portion of the carbureter body and in which the discharge nozzle is fixed.

Figs. 14, 15 and 16, are diagrammatic plans illustrating various manners in which 85 the actuating parts may be associated with one another, and

Fig. 17, is a sectional elevation of the end of the spraying nozzle illustrating an auxiliary chamber which may be employed in 90 conjunction therewith,

In carrying out my invention, as illustrated in the drawing, I employ two hollow cylindrical bodies *a* and *u* secured at the lower parts to an arm *k*. These parts may 95 be made integral as shown. The body *a* is a tank provided at its bottom with a screw threaded neck *J* by which it is connected to the liquid fuel supply pipe. The neck *J* is connected by a passage *e* with the interior 100 of the tank and this is controlled by a needle *d*. The needle *d* is actuated by levers *c* and *c'* which are pivoted in lugs on the cover *f*, the levers *c* and *c'* being operated by a float *b*. The cover *f* rests on the upper edge of 105 the body *a* and a spring *g* connected by a screw *h* to the body *u* bears against the cover *f* to maintain the same in place. By turning the spring *g* on the screw *h*, the cover *f* is released and may be removed with 110

the levers c and c' , the needle d , and the float b , to clean the tank a . The float b and levers c and c' so actuate the needle d as to maintain a constant liquid level in the tank.

5 The tank a communicates with the body u^1 by a passage l (Fig. 1) provided in the arm k . This passage is connected with a chamber m bounded laterally by the inner wall of the body u^1 , on the top part by a 10 disk n , and on the bottom by a plate p screwed in the body u^1 and provided with a draw-off cock s . Between the body u^1 and the bottom-plate p there is a gasket r . The disk n is maintained against a flange q inside the body u^1 by means of a spiral spring o extending between the plate p and the disk n , and a tight joint between these members may be made in any suitable manner.

In the disk n is screwed a spraying nozzle t (Fig. 1) which is set exactly in the longitudinal center of the body u^1 and is provided with an axial bore t^1 and an eccentric port t^2 in its upper end, (Figs. 10, 11 and 12). I also employ a cover or cap v provided with a port x of same diameter as the port t^2 , and mounted on an arm w , to turn on the spraying nozzle t , so that, depending upon the position of cover v , the port x may be made to register exactly with 25 the port t^2 , or to close it more or less as is shown in the Figs. 10, 11 and 12; thereby regulating the supply of the liquid fuel as the requirements of the motor may vary.

30 The cover v is provided with a spring G^2 under tension and surrounding the spraying nozzle and its cover to maintain the latter in position. This spring is fixed at one end to the base of spraying nozzle and at the other end to the arm w . The spraying nozzle t is in a mixing chamber u in the body u^1 in which there are apertures, such as A^1 , for the admission of air to the carbureter, and also with a rectangular aperture B^2 by which it is possible to adjust the revoluble position of the spraying nozzle t by means of a key. It will thus be apparent that the position in which the port in the cover v is coincident with the port in the spraying nozzle t , it may be adjusted to determine the relative positions of these ports relatively to the extent to which the opening or port made by the iris diaphragm hereinafter described is opened. This mixing chamber is in connection with a neck 45 A^5 through which the combustible mixture is conveyed in being fed to the motor.

50 The opening in the neck A^5 is adjustable by means of an iris diaphragm B^1 (Figs. 1, 2, 4, 5, 6) composed of three arc shaped plates C^1 , C^2 , C^3 , each of which is provided on one of its faces adjacent one end with a pivot pin D^1 , D^2 , D^3 , and with a working pin E^1 , E^2 , E^3 , on the other face adjacent the other end. The pivot pins are engaged 55 in apertures F^1 in the neck A^5 , and the

working pins in radial slots E^4 , E^5 , E^6 (Fig. 9) in a ring G^1 , which is provided with a hand-lever H^1 . By moving the hand-lever H^1 in one direction the ring G^1 is turned and the radial slots E^4 , E^5 , E^6 cause the 70 working pins E^1 , E^2 , E^3 to move toward the longitudinal center of body u^1 , swinging the plates C^1 , C^2 , C^3 so that the opening between them is reduced. This throttles the admission and causes the motor to go slower. If 75 the ring G^1 is moved in the opposite direction, the opening between the plates is enlarged. The said ring G^1 is mounted on the lower portion of the neck A^5 from which the hand-lever H^1 extends through a lateral 80 aperture, and is also provided with a flange G^4 in which there are three recesses G^5 . The arm w of the spraying nozzle cover v engages one of the other of these three notches so that the cover v is caused to rotate with the ring G^1 . This ring G^1 bears against a convex washer I (Fig. 8) provided with four radial equidistant notches K^1 , K^2 , K^3 , K^4 . It assumes the form of a spring and is placed between the ring G^1 and another ring J^1 , 90 so that it may be turned with a special key. The function of the ring J^1 is to take up 95 the wear between the plates C^1 , C^2 , C^3 of the iris diaphragm B^1 ; and also by screwing or unscrewing it, to make it possible to adjust the position of the lateral aperture through which the hand-lever H^1 passes 100 and consequently the hand-lever H^1 itself into different positions by shifting the position of the neck A^5 with regard to the parts a , u^1 and k as shown by Figs. 14, 15 105 and 16. The ring J^1 is provided also with three slots J^2 , J^3 , J^4 , starting from a threaded hole J^5 ; the slot J^2 is concentric to the axis of J^1 , the other two slots J^3 and J^4 are rectilinear and directed toward the 110 outer and inner edge of the ring J^1 ; a conical binding-screw L^1 is arranged to be screwed into the threaded hole J^5 thereby pressing apart the two parts of the slotted ring J^1 and forcing the neck A^5 against the 115 body u^1 .

When in the positions shown in the drawings the iris-diaphragm B^1 is fully opened (Fig. 4), the two ports x and t^2 are coincident (Fig. 10), so that the passage there-through is not obstructed at all (Fig. 1) and the quantity of liquid-fuel delivered through the same is a maximum. Now if the hand-lever H^1 is rotated in a clockwise direction, the passage between the plates C^1 , C^2 , C^3 , decreases (Fig. 6) and the two ports x and t^2 do not remain exactly coincident (Fig. 11). The passage of the combustible mixture is throttled so that the delivered quantity of liquid-fuel by the spraying-noz- 120 125 130

zle is reduced. At last, when the hand-lever H^1 is carried clockwise to its extreme position, the opening between the plates is a minimum (Fig. 5) and the two ports have 5 only very small portions of their openings corresponding with one another (Fig. 12). In any case, however, the liquid drawn out of the spraying nozzle t is delivered to the central portion of the passage between the 10 plates. This is especially the case when the passage between the plates is reduced to its minimum, so that the suction of the engine works directly on the spraying nozzle.

In the drawing as hereinbefore indicated, 15 the parts of the carbureter are shown as set in the positions for normal use, that is to say, in the positions in which the port in the cover or cap is coincident with the port in the end of the spraying nozzle when the 20 iris diaphragm is opened to its fullest extent. The revoluble position of the spraying nozzle however, as hereinbefore indicated, may be adjusted by turning the disk n so as to bring the port in the end of the 25 spraying nozzle to a place in which it will be entirely uncovered by the port in the cover or cap before the iris diaphragm is opened to its fullest extent so that in the continued opening of the iris diaphragm 30 the continued movement of the cover or cap will progressively close the port in the end of the spraying nozzle, this adjustment being useful when the carbureter is operating in a rarefied atmosphere to enable an increased admission of air with the correspondingly decreased supply of liquid fuel, as for example, in connection with aeroplane motors in flying a considerable distance 35 above the surface of the earth.

40 It must be well understood that the described construction is given by way of example only and that the details of the same and the relative dimensions of the different parts may differ without departing from 45 the scope of the invention as hereinafter claimed.

The spraying-nozzle t may be provided with a conoidal member w^1 surrounding it, and extending to the hand-lever w . The 50 chamber w^2 between it and the spraying nozzle is filled with liquid fuel when the motor stands still, so that the spraying nozzle is copiously fed when next started. For this purpose the level of the fuel in the cylindrical body a is fixed for instance, at one millimeter lower than the top of the spraying nozzle t , but at four millimeters over a small port z which is placed in the spraying nozzle with which another small port z^1 55 in the cover v (see Fig. 17) comes into juxtaposition when the ring G^1 is in the shut off position so that the aforesaid chamber fills itself as soon as the motor stands still and causes no suction at all. The chamber 60 u may have one or more apertures A^1 for

the suction of warm air and be provided with baffle-plates or air-channels O^2 , O^3 , controlling the air passage to the top of the spraying-nozzle. When the conoidal member w^1 is employed it will naturally reduce 70 the area of the air passages by substantially closing the channel o^3 .

I claim as my invention:

1. A carbureter comprising a casing, a spraying nozzle having a discharge port 75 therein, a cap fitting over the spraying nozzle and also having a port therein adapted to open the port in the spraying nozzle a predetermined extent, a diaphragm adjustable to vary the opening therein, means for simultaneously operating the diaphragm and the cap to vary the opening in the diaphragm and determine the corresponding extent to which the port in the cap opens the port in the spraying nozzle, and means for 80 varying the position of the spraying nozzle to determine the place at which the ports in the cap and the spraying nozzle are coincident relatively to the extent of the opening in the diaphragm. 85

2. A carbureter comprising a casing, a spraying nozzle having a discharge port in the end thereof, a cap fitting over the end of the spraying nozzle and having a port therein adapted to open the port in the end 90 of the spraying nozzle a predetermined extent, an iris diaphragm adjustable to position to vary the extent of the opening therein, means for simultaneously operating the diaphragm and cap to vary the size of the 95 opening in the diaphragm and correspondingly vary the extent to which the port in the cap opens the port in the end of the spraying nozzle, and means for varying the revoluble position of the spraying nozzle to 100 determine the place at which the ports in the cap and the end of the spraying nozzle are coincident relatively to the extent of the opening in the iris diaphragm. 105

3. A carbureter comprising a casing, a 110 spraying nozzle having a discharge port in the end thereof, a cap fitting over the end of the spraying nozzle and having a port therein adapted to open the port in the end of the spraying nozzle a predetermined extent, an iris diaphragm adjustable to position to vary the extent of the opening therein, means for simultaneously operating a 115 diaphragm and cap to vary the size of the opening in the diaphragm and correspondingly vary the extent to which the port in the cap opens the port in the end of the spraying nozzle, a disk mounted in the casing and in which the spraying nozzle is secured, and a spring for yieldingly maintaining the spraying nozzle and disk in position so that the same may be adjusted revolubly to determine the position of the discharge port in the spraying nozzle at which the same is coincident with the port in the 120 125 130 135 140 145 150 155 160 165 170 175 180

cap relatively to the extent of the opening of the iris diaphragm.

4. A carburetor comprising a casing, a spraying nozzle having a discharge port therein, a cover member on the spraying nozzle and provided with a port therein; means for moving said cover member to determine the extent to which the discharge port in the spraying nozzle is open, a supply tank, means providing communication between the said supply tank and spraying nozzle, and a member attached to the end of

the spraying nozzle surrounding the same, and provided with a port which when the discharge port in the spraying nozzle is closed is open to the interior of the spraying nozzle so as to receive a charge of liquid from said supply tank.

In testimony whereof I have affixed my signature in presence of two witnesses.
